UNITED STATES PATENT OFFICE.

FRANK LYMAN, OF FRESNO, CALIFORNIA.

FRUIT-SEEDER.

No. 908,588.

Specification of Letters Patent.

Patented Jan. 5, 1909.

Application filed March 19, 1908. Serial No. 422,174.

To all whom it may concern:

Be it known that I, FRANK LYMAN, a citizen of the United States, residing at Fresno, in the county of Fresno and State of California, have invented certain new and useful Improvements in Fruit-Seeders, of which the following is a specification.

My invention relates to fruit seeding machines, and it consists in the construction and arrangement of parts, as will be herein-after described and particularly pointed out in the claim.

Description of the Drawings.

15 In the drawings, similar letters of reference indicate corresponding parts in all the figures. Figure 1—is a central longitudinal section of my improved seeding machine, with a portion indicated in side elevation. Fig. 2—20 represents a longitudinal sectional elevation of the large elastic pressing roller, broken away centrally. Fig. 3—is an end elevation of the same, with a portion in section. Fig. 4—is a longitudinal section of the rotary brush 25 or impaling pin cylinder, centrally broken away. Fig. 5—is a transverse section of said cylinder partly in elevation, indicating the impaling pins thereon. Fig. 6—is an enlarged view of one of the impaling pin segments. Fig. 7—is a cross section of Fig. 6, 30 indicating the means for holding the various sectional segments from becoming parted. Fig. 8—represents, respectively, side elevation and side or edge view of one of the numerous 35 stripping devices. Fig. 9—indicates a side elevation, and also a section of one completed stripping-brush ring.

General Description.

40 The frame-work, A, of this machine can be composed of any kind of material, and has sides only, the ends being open. Said sides are tied together by suitable tie-bolts, not shown in the drawing. This frame has recesses, B, C and D, for receiving suitable 45 boxes, which are adjustable so as to regulate the proximity of the various cylinders or rollers, not only to compensate for wear of the various parts, but to accommodate various sized fruits.

The boxes E, F and G afford bearings for shafts H, I and K, respectively. Shafts H and K, respectively, carry the feed cylinder or roller L and the pin-roller or cylinder M, 50 and the shaft I supports the stripping roller

or cylinder N. On the upper part of the frame A is an angular recess O which supports an adjustable box P. Said box P is provided with a set screw 4 and a cap Q, so as to adjust the small feed roller R on its 60 shaft S. This feed roller almost contacts the large feed roller L, so as to crush the fruit when passing between them, to prevent crushing the seeds of the raisins or other fruit that may pass between said rollers. 65 The surface of said rollers L and R have rubber coverings of considerable thickness, 30 and 31. On the inner surfaces of said rubber coverings are guttapercha linings, 32.

Immediately above the roller L is a conveyor-trough, 35, which is agitated in the rear portion thereof by suitable devices, not shown in the drawings, for allowing the fruit to drop into the hopper U, from whence it is conveyed to and between the rollers L and R, 70 when the rubber surfaces of said rollers crush the fruit which drops on the pin-roller or cylinder M, and as the fruit is crushed it piles up somewhat between the pin-roller and the feed-roller L, whereby it passes into the recesses between the impaling pins V, where it becomes packed, the seeds of the fruit being larger than the spaces between said pins, and the seeds are impaled and remain on the points of the pins V until the revolving of the 85 pin-roller M brings them opposite the stripping roller N, when the latter, which revolves rapidly, removes the seeds from the pin-roll, as said rolls revolve in opposite directions. As the pin-roll continues to 90 revolve, the crushed fruit between the impaling pins contacts with the stripper fingers W, when it drops in a mass into a suitable receptacle as a finished product.

The stripping roller N is cleaned by fingers 95 Y, mounted on a shaft Z, and secured adjustably by set screws 7.

The stripping fingers W are mounted on a shaft 20, and held in an adjustable position by set screws 21.

The box E, of the large feed wheel L, is also adjustable by means of bolts or set screws 23. Also, the stripping roller is provided with adjustable screws 22 and a lock-nut 25, so as to hold the parts in position 105 after adjustment.

The impaling pin roller is composed of a number of segments (see Fig. 6 of the accompanying drawings). These segments 27 have projecting ribs 28 and recesses 29 (see 110

Fig. 7, where these parts are fully illustrated). The object of these parts 28 and 29 is to hold the various segments together and bind them so that they will not slip apart when 5 revolving rapidly.

In Fig. 4, the shaft K has mounted thereon two disks 31, and on these disks is secured a thin cylindrical shell 30, on which the pin segments are mounted, and the washers 32 hold these pin segments in place through the medium of the nuts 33 on opposite ends of the shaft K. The pin segments 27, being 10 arc-shaped, and having the projections 28 and recesses 29 therein, become bound together similar to a solid cylinder, as the pressure of the washers 32 against said segments hold them securely through the medium of the nuts 33.

The seed stripping brush is made up of many 20 annular rings (see Fig. 9), and the steel pins therein are held in position by cast metal that surrounds them and which forms the rings N. The seed stripping brush cylinder has a clamping device similar in part to the 25 clamping device indicated in Fig. 4, which is

clamped by suitable washers and nuts on its supporting shaft.

Having described the invention, that which I desire to claim by Letters-Patent is:—

30 A fruit seeding device of the character described, the combination of adjustable feed- or crushing-rollers provided with elastic surfaces, an impaling pin-cylinder contacting with one of said rollers, a conveyance mounted above said feed-rollers for feeding fruit to said rollers through the medium of a hopper; means for stripping the fruit from said impaling pin-cylinder, a rotary stripping brush for removing the seeds from the ends of the 35 impaling pins of said pin-cylinder, and adjustably fixed fingers for cleaning the rotary brush.

40 In testimony whereof I affix my signature in presence of two witnesses.

FRANK LYMAN.
